[57] CLAIM

The ornamental design for edge trim surface treatment for a chair, as shown and described.

DESCRIPTION

FIG. 1 is a perspective view of edge trim surface treatment for a chair showing our new design.

FIG. 2 is a left side view, the right side view being a mirror image thereof.

FIG. 3 is a front view.

FIG. 4 is a rear view.

FIG. 5 is a top view; and,

FIG. 6 is a bottom view.

The broken line showing of a chair is for illustrative purposes only and forms no part of the claimed design.
